Primary Examiner — Holly E Thurman

Assistant Examiner — Altaira J Swangin

(57) **CLAIM**

The ornamental design for a cake shield, as shown and described.

DESCRIPTION

FIG. 1 is a top perspective view of the cake shield, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view of the cake shield of FIG. 1, shown in use.

The broken lines in the drawings show portions of the cake shield and form no part of the claimed design. The additional broken lines in FIG. 8, showing a cake and candles, show environment and form no part thereof.

1 Claim, 8 Drawing Sheets
